INDEXING MEANS FOR CONTINUOUS
MINING MACHINE HEADS

Joseph J. Slomer, Chicago, Ill., assignor to Goodman Manufacturing Company, Chicago, Ill., a corporation of Illinois

Application December 23, 1950, Serial No. 202,503

10 Claims. (Cl. 262—29)

1

This invention relates generally to mining and particularly to improvements in machines such as a continuous mining and loading machine and the like.

In a continuous mining and loading machine, as disclosed for example in the co-pending application of Frank Cartlidge, Serial No. 116,684, filed September 20, 1949, the Cartlidge application and this application having a common assignee, a cutting and dislodging head is carried at the end of a boom for side to side swinging movement, up and down tilting movement, and forward and backward reciprocating movement with respect to a face being mined. Mining operations may be started by a vertical sweep of the head along one side or edge of the face. Following this initial sweep the head is swung, some amount less than its width, toward the other side or edge of the face to index it for the next vertical sweep. Such vertical sweeps and sidewise indexing movements are repeated automatically until the face is completely mined out, from one side to the other.

When the head is operating against the face, visibility is reduced due to the fines and dust thrown into the air. This reduction in visibility makes it difficult at times for the operator to index the head accurately by any sort of manually operated control apparatus. In very dusty locations, therefore, it is necessary for most efficient operation that the machine be capable of indexing itself from one position to the next without the operator attempting to control the magnitude of the movement.

Accordingly, a principal object of the present invention is the provision of an operating and control system for such a cutting and dislodging head which will automatically line up the head with the next portion of the face to be cut.

In a continuous miner of the type disclosed in the above-mentioned application, gathering mechanism is provided at the floor level for picking up material dislodged by the head. It is desirable that the dislodged material be directed downward in line with gathering mechanism and not thrown outward from it. In order to direct the dislodged material properly it is essential that the cutter head overlap to a certain extent the portion of the face being mined. For example, where the cutter head is, say, 42 inches wide, the actual width of face acted against, after the first sweep, must be something less than 42 inches so the overlap will direct the dislodged material toward the gathering mechanism. In some very hard coals, for instance, this overlap may be as little as 2 inches while in other softer and more

2

frangible coals it may need be as much as 6 or 8 inches. Thus it will be apparent that any automatic indexing system must be readily capable for varying amounts of overlap to operate most efficiently under varying mining conditions. For example, the above-mentioned 42 inch wide head should be capable of varied indexing movement from full width to some amount considerably less than full width.

10 Accordingly, it is another object of the present invention to provide such an operating and control system which is adjustable to automatically index the head in varying amounts depending on the mining conditions.

15 Another object is the provision of such an operating and control system in which the cutting and dislodging head is selectively operable to index the head in either direction a predetermined proportion of its full swing and is further operable 20 selectively to swing the head in either direction any desired amount up to a full swing in a single pass.

25 In one specific form the invention includes provision of fluid metering means which, when actuated, supplies a measured quantity of fluid which is utilized to control indexing movement of the head to an extent determined by the measured quantity of fluid. An ancillary feature includes the provision of means for adjusting the 30 quantity of fluid measured in order to correspondingly adjustably vary the indexing movement of the head.

35 A preferred form of the invention as illustrated in the drawings includes reversible fluid pressure operable motor means for swinging the head in opposite directions. A pair of metering cylinders is provided, each being connected to a source of fluid and each being operable to draw a measured quantity of fluid from the source and supply it to 40 the motor means to index the head a corresponding measured amount in one direction or the other. Manually operable control means is additionally provided to selectively actuate either of the metering cylinders for indexing movement in 45 either direction and to selectively actuate the head for a continuous swing in either direction where desired.

50 Other objects and advantages will be apparent from the following description taken in connection with the appended drawings in which:

Figure 1 is a plan view of a continuous mining machine embodying a preferred form of an operating and control system in accordance with the present invention; for clarity, the machine itself 55 is superimposed lightly over the operating and

control mechanism to better show the environment for the latter;

Fig. 2 is a fragmentary longitudinal side view of Fig. 1;

Fig. 3 is a diagrammatic plan view of the system showing it in a neutral condition with the pump running and with the cutting head swung to the right;

Fig. 4 is a view similar to Fig. 3 showing the system in condition for indexing movement to the left;

Fig. 5 is a view similar to Fig. 4 showing the metering means being recharged for a subsequent indexing movement;

Fig. 6 is a view similar to Fig. 4 but showing the system in condition for indexing movement to the right;

Fig. 7 is a view similar to Fig. 3 but showing the system in condition for continuous traversing movement toward the left;

Fig. 8 is a view similar to Fig. 7 but showing the system in condition for continuous traversing movement toward the right;

Fig. 9 is an enlarged cross-sectional view of a portion of the operating and control system showing means for adjusting the magnitude of indexing movement; and

Fig. 10 is a diagrammatic view, similar to Fig. 3, of a modified form of operating and control system.

Referring now more particularly to the embodiment shown in the drawings, Fig. 1 illustrates a continuous mining machine such as disclosed in detail in the above-mentioned co-pending patent application.

Briefly, the machine comprises a main frame A having a sub-frame or turntable B mounted for side to side swinging movement. On the turntable is a reciprocable frame C which is mounted for forward and backward movement with respect to the turntable B. The reciprocable frame C carries a drum-shaped cutting and dislodging head D which is mounted for up and down tilting movement about an axis E—E. Beneath the head is a gathering mechanism F arranged to transfer dislodged material to a conveyor G which runs along the swingable frame B, the main frame A, and a swingable rear unloading boom H. For additional details of the mining and loading machine, reference should be made to the above-mentioned co-pending application.

Referring now more particularly to the operating and control system which is the object of the present invention, a pair of cylinders 21 and 21a is mounted, as by bolts 22, to the main frame, along opposite sides of the conveyor G. Internally of the cylinders, pistons 23 and 23a (Figs. 3-8) are fitted and they carry piston rods 24 and 24a, respectively. Sheaves 26 and 26a, respectively, are carried by the ends of the piston rods.

The turntable B is provided with a circular portion 27 defined between upper and lower flanges 28 and 29 (Fig. 2). A cable 31 has one end portion mounted on the main frame at 32 and it extends backwardly therefrom, around sheave 26 and forwardly to the turntable portion 27, approximately half way therearound to point 33 where it is anchored by suitable means, on around the turntable, backwardly to sheave 26a, around the latter, and forwardly to point 34 where the other end is fixed to the opposite side of the frame. By this arrangement, pressure admitted to the head end of cylinder 21 will extend piston rod 24, causing the turntable to be swung clockwise to the position shown in Fig.

1 while at the same time causing piston rod 24a to be contracted. Conversely, pressure introduced into the head end of cylinder 21a will cause the turntable to swing counter-clockwise to a position opposite that shown in Fig. 1.

5 In order to more effectively tie-in Fig. 1 with the diagrammatic views which follow it, the longitudinal center line of the turntable B (and, likewise, that of the cutting and dislodging head 10 D) is indicated "O—T" throughout.

It should be understood that the views shown in Figs. 3-8 and in Fig. 10 are diagrammatic, for the purpose of more clearly describing the invention, the dimensions and proportions not necessarily being any where near those that would be proper for an actual installation.

Referring now more particularly to the novel operating and control system, as illustrated in Fig. 3, a valve block 36 is formed with three bores, 37, 38 and 39, containing, respectively, valve spools 41, 42 and 43. Valve bore 37 is provided with circumferential grooves 44, 46, 47, 48 and 49. Valve bore 38 is formed with grooves 51, 52, 53, 54, 56, 57 and 58. Valve bore 39 is formed with grooves 59, 61, 62, 63, 64 and 66.

20 Valve spool 41 is formed with diametrical reductions 67, 68 and 69 alternating with lands 71, 72, 73 and 74. Valve spool 42 is formed with reductions 76, 77 and 78 which alternate with lands 79, 81, 82 and 83. Valve spool 43 is formed with reductions 84, 86 and 87 which alternate with lands 88, 89, 91 and 92.

30 Centering means for maintaining each valve spool in the "neutral" position of Fig. 3 includes a cap 93, having an interior shouldered portion 94, mounted by any suitable means to cover the end of the valve spool. The corresponding end of each valve spool is diametrically reduced at 95 and 97 to provide outwardly disposed shoulders 98 and 99 and inwardly disposed shoulders 101 and 102. Washers 103 and 104 are suitably mounted on the reductions 96 and 97, respectively. A coil spring 106 bears, respectively, on the two washers tending to bias them apart. 40 Thus, as shown in Fig. 3, the spring urges the washer 103 upward into engagement with the outer surface 107 of the valve casing and urges the washer 104 downward against the shouldered portion 94. The parts are so dimensioned that under these conditions the shoulder 98 of each valve spool is flush with the end of the casing so as to maintain the spool in the neutral position shown in Fig. 3. As shown in Fig. 6, upward movement of the valve spool is limited by engagement of shoulder 101 with the washer 103. Conversely, as shown in Fig. 4, downward movement of each valve spool is limited by engagement of shoulder 99 with washer 104.

45 Referring further to Fig. 3, the valve block includes an intake port or opening 108 which, when all the valve spools are in neutral positions, communicates directly with an outlet port 109 through passages 111, 112, 113, and 114. An overload bypass passageway 116, entrance to 50 which is controlled by relief valve 117, provides for bypassing fluid directly from port 108 to port 109 at times. Branching from port 108 is another series of passageways 118, 119 and 121 connecting grooves 46, 53 and 62 and into which entrance 55 is controlled by check valve 122. An inlet-outlet port 123 is connected by passage 124 to groove 63; similarly an inlet-outlet port 126 is connected by passage 127 to groove 45. An outlet passage 128 provides communication between 60 grooves 44, 51, 59 and the port 109. An inlet 65

outlet port 129 is connected by passage 131 to a cross passage 132 which provides communication with both grooves 50 and 54; similarly, an inlet-outlet port 133 is connected by passage 134 to a cross passage 136 which provides communication with both grooves 52 and 61. At an intermediate level a through passage 137 provides communication between port 109 and grooves 47, 56 and valve bore 39, when valve spool 43 is in the Figure 3 position.

Metering means for rotatably driving the turntable portion 27 to index the cutting and dislodging head a predetermined proportion of its full swing to the right or to the left includes a pair of expandable casings 138 and 138a having movable walls 139 and 139a, respectively, and defining metering chambers 141 and 141a which are variable in volume with movement of the walls. As best shown in enlarged detail in Fig. 9, the casings 138 and 138a may be cylinders and the movable walls may be pistons movable therewithin.

Metering cylinder 138 will now be described in detail, it being understood that, except for differences specifically described, it is the same as cylinder 138a, similar parts in the latter being designated by the same reference characters followed by "a".

Metering cylinder 138 comprises an elongated tubular casing having an inlet port 142 and an outlet port 143. At the opposite end is a flange 144 having drilled and tapped holes 146. An end closure piece 147 is attached to the flange by means of bolts 148 threadably engaged in the bolt holes 146. A gasket 149 is interposed between the flange and closure for fluid sealing purposes. Centrally of the closure is a drilled and tapped pressure port 151. The upper end of the cylinder 138 is provided with an internal concentric sleeve 152 having internal threads 153 near the outer end. At its inner end, the sleeve 152 is provided with an internal groove 154 carrying a fluid sealing O-ring 156. The piston 139, in this case, is of the "floating" type and comprises a pair of circular discs 157 and 158 having oppositely disposed rubber or leather cup members 161 and 162 compressibly interposed between them by means of center bolt 159. The disc 158 is provided with an exteriorly extending skirt 163 which engages the cap 147 to limit outward movement of the piston.

The piston is biased in a direction to expand the metering chamber 141 to its maximum volume by means of a coil spring 164 which bears respectively on the upper end of the casing and on the inner face of the floating piston.

Adjustable stopping means 166 is provided within the cylinder casing for limiting the inward travel of the piston to limit the minimum volume condition of the metering chamber. This stopping means in the present case comprises a stem-like member having a smooth inner portion 167 which extends in fluid sealing relationship through the O-ring 156. The outer portion of the stem 166 is threaded as at 168 for engagement with the casing threads 153. Thus it will be seen, that by screwing the stem 166 outward the minimum volume condition of the metering chamber will be reduced; conversely, by screwing it inward, toward the piston 139, it will be increased.

As will be seen subsequently, fluid metered by the cylinder 138 will be supplied to the operating cylinder 21 to index the cutting head to the right; conversely, fluid metered by the cylinder 138a will be supplied to the operating cylinder

21a to index the cutting head to the left. Normally, it will be desired that these indexing movements be of the same magnitude in both directions. This means that the volume of fluid supplied by each of the metering cylinders should be the same and this is accomplished by maintaining the adjustment stems 166 and 166a at corresponding levels within their respective cylinders.

10 The adjusting stems 166 and 166a are maintained at the same relative levels by providing opposite hand threads (for example right hand for thread 163 and left hand for 168a) and mechanically interlocking them through a pair of 15 meshed gears 169 and 169a. At the same time it is necessary to provide for adjustment of one with respect to the other. The details of this construction are as follows, as shown in Fig. 9: At the upper end of stem 166a a flange 171 is 20 provided. Above the flange is a milled slot containing a key 172 and above that are additional threads 173. The gear 169a has a keyway 174 which fits over the key 172 and maintains the gear and stem against relative rotation. The 25 gear is held in place by nut 175 and washer 177 which press it against the flange 171. Gear 169 is mounted so that, when desired, it may be rotated free of its stem 166, being frictionally engaged between a lower lock nut 178 and upper 30 washer and nut 179 and 181, respectively. A lock nut 182 on the threaded portion 168a of stem 166a holds the two stems in their adjusted positions.

To carry out identical adjusting movements of 35 both stems, in the same direction and magnitude, it is necessary only to loosen the lock nut 182 and turn the gears in one way or the other. If it is desired to correct a condition where one metering cylinder is supplying more fluid than the other, this can be done simply by loosening nut 181 of gear 169 without rotating its stem, following which stem 166a can be turned up or down to match the level of stem 166.

The various elements of the operating and 40 control system shown in Fig. 3 are interconnected by circuit means as follows: the head end of operating cylinder 21 communicates with control valve port 129 through conduit 183; similarly the head end of operating cylinder 21a communicates with control valve port 133 through conduit 184. A pump 186 is located in conduit 187 and is adapted to draw fluid from a tank or reservoir 188 and supply it to control valve port 108. Control valve outlet port 189 is connected 45 by conduit 189 to return fluid to the tank. A supply conduit 191 containing check valve 192 is connected between the tank and metering cylinder inlet port 142; similarly another supply conduit 191a containing a check valve 192a is 50 connected between the tank and the metering cylinder inlet port 142a. Conduit 193 containing check valve 194 is connected between metering cylinder outlet port 143 and conduit 183; similarly conduit 193a containing check valve 194a is 55 connected between metering cylinder outlet port 143a and conduit 184.

OPERATION

70 When the miner is in operation the pump 186 may normally be running continuously. In the neutral condition of the control valve means 36, as shown in Fig. 3, the pumped fluid will be bypassed to tank in the direction indicated by the 75 arrows.

Indexing to the left

Referring now to Fig. 1, assume the miner has cut a vertical sweep along the right hand side of the face, as indicated at S, and that it is to be indexed to its left to make a succeeding cut indicated S-S, the lines of the two cuts overlapping an amount "X" predetermined by the metering means. This is carried out as shown in Fig. 4, simply by depressing the valve spool 41. This causes the land 73 to close off communication between passages 111 and 112 and divert fluid under pressure past check valve 122 through passage 118 and out of groove 46 (now uncovered by land 72) and into conduit 196a leading to the metering cylinder 138a. The fluid under pressure will move piston 139a upward, compressing spring 164a and forcing fluid out of the meter chamber 141a into the head end of operating cylinder 21a which will exert a tension on rope 31 to pull the turntable portion 27 to the left (counter-clockwise) an amount determined by the measured amount of fluid supplied by the metering cylinder. At the same time the tension exerted on the cable 31 will move the piston 23 into its cylinder causing an amount of fluid equivalent to the measured amount to be returned to tank 188 through the conduit and control valve means in the direction of the arrows shown in Fig. 4.

The operator will maintain the valve spool 41 depressed until the indexing operation is completed. When the head stops swinging, as it will do automatically, the operator releases the valve spool and its centering spring 106 automatically moves it back to neutral position.

Recharging metering cylinder at the end of indexing step

After the above-described leftwise indexing movement, and as soon as the operator releases the valve spool to neutral position, the biasing spring 164a will push the piston 139a downward returning fluid beneath the piston to tank, through the control valve means, and drawing additional fluid into the metering chamber from the tank, all as indicated by the arrows in Fig. 5. The system is now recharged, ready for a subsequent leftwise indexing movement.

Indexing to the right

To index the cutting head to the right the operator pulls valve spool 43 out to the position shown in Fig. 6 and holds it there until the indexing movement is automatically completed. This causes valve land 92 to block off communication between passages 113 and 114 and diverts pressure fluid past the check valve 122, through the passage 121 (now opened by land 89) into the conduit 196 leading to the metering cylinder 138. The pressure so admitted to the floating piston 139 displaces it upward against the bias of spring 164 until it is stopped by engagement with the end of stem 166. The resultant contraction in volume of the metering chamber 141 forces a measured quantity of fluid into the head end of operating cylinder 21 thereby exerting a tension on the cable 31 to rotate the turntable 27 to the right (clockwise) an extent determined by the measured volume of fluid displaced from the metering chamber. This is accompanied by inward movement of the opposite operating piston 23a and an amount of fluid equivalent to the measured amount is discharged from the head end of cylinder 21a, through the control valve means, all as shown by the arrows in Fig. 6. As soon as the operator releases the valve spool 43

and lets it return to neutral position, the metering cylinder 138 will be automatically recharged, for subsequent rightwise indexing movement, in the manner described in connection with Fig. 5.

5 *Continuous traversing movement to the left*

To swing the head to the left (counter-clockwise) in any desired amount other than the predetermined amount set by the metering means 10 the operator depresses the valve spool 42 as shown in Fig. 7. This causes land 82 to shut off communication between passages 112 and 113 and diverts fluid under pressure past the check valve 122, out of the passage 119 (now opened by land 81) into conduit 184 leading to the head end of operating cylinder 21a. Fluid is correspondingly displaced from the head end of the other operating cylinder as the turntable swings to the left and is returned to tank through the control valve 20 means, all as indicated by the arrows shown in Fig. 7. Under this condition leftwise traversing is completely under the control of the operator. It starts when he depresses the spool 42 and it stops when he releases it. He can swing the 25 head only a few inches or, if he desires, he can swing it in one continuous traverse completely from the right to the left side of the room.

Continuous traversing movement to the right

30 Fig. 8 illustrates the reverse of the condition described above in connection with Fig. 7. To swing to the right the operator pulls the valve spool 42 outward. This causes land 83 to shut off communication between passages 112 and 113 and diverts fluid under pressure past the check valve 122 out of passage 119 (uncovered by land 81) to the conduit 183 leading to the head end of operating cylinder 21. This will cause the turntable to swing to the right and fluid will correspondingly be displaced from the head end of the other operating cylinder, through the control valve means, to tank, all as indicated by arrows in Fig. 8. This rightwise swinging movement is also completely under the control of the operator who is able to inch the head from left to right a little at a time or to traverse the whole face from left to right if he desires.

Modified arrangement for actuating the metering means

50 One of the basic features of the present invention resides in actuating the metering means 138-138a to produce a measured quantity of fluid and then providing other means for swinging the head a definite proportion of its full 55 swing as determined by that measured quantity of fluid. The metering means may be actuated in any suitable manner. This invention, therefore, is not limited to the specific fluid pressure actuated means disclosed in Figs. 3-9. For example, instead of actuating the metering pistons 139-139a by fluid pressure conducted through conduits 196-196a, this may be done mechanically by some arrangement such as shown in Fig. 10.

60 Fig. 10 is essentially the same as Fig. 3 with the control valve means simplified by eliminating spools 41 and 43 and by providing mechanical rack and pinion arrangements for moving the metering pistons inward against their biasing 65 springs.

70 Thus in the neutral condition shown in Fig. 10 the pump will bypass fluid directly to the tank through the valve by reason of the fact that the spool reduction 278 is in alignment with the 75 passages 211 and 214.

To index the turntable to the left the operator pulls downward on lever 197a. This turns segmental pinion 198a in a direction to move rack 199a upward thereby moving the metering piston 139a upward into its casing. This will transfer a measured quantity of fluid into the head end of operating cylinder 21a to index the turntable leftwise as described in connection with Fig. 4.

To index the turntable to the right the operator pulls down on the lever 197 thereby turning segmental pinion 198 in a direction to move rack 199 upward. This displaces the metering piston 139 upward into its casing and index the turntable to the right as described in connection with Fig. 6.

Recharging of the metering cylinders after the indexing steps will be exactly the same as described in connection with Fig. 5.

To traverse the head in any desired amount in a leftwise direction the operator depresses the valve spool 242. This causes land 282 to shut off communication between passages 211 and 214 and divert fluid under pressure past the check valve 222 and out of the passage 218 (now uncovered by land 272) into conduit 184 leading to the head end of operating cylinder 21a. A corresponding amount of fluid will be displaced from the head end of cylinder 21 as the turntable swings to the left, the displaced fluid passing through conduit 183 through groove 256 (now uncovered by land 282) and out of passage 231, returning to tank through conduit 189.

To traverse the head in any desired amount in a rightwise direction the operator pulls the valve spool 242 upward. This causes the land 283 to shut off communication between passages 211 and 214 and divert fluid under pressure past the check valve 222 (uncovered by land 272) into conduit 183 leading to the head end of operating cylinder 21. As the turntable swings to the right fluid will be displaced from the head end of operating cylinder 21a and will pass through conduit 184, groove 251 (uncovered by land 279), into passage 228 and to tank by way of conduit 189.

While two forms in which the present invention may be embodied have been shown and described it will be understood that various modifications and variations thereof may be effective without departing from the spirit and scope of the invention as defined by the appended claims.

I claim:

1. In a continuous mining machine, a cutting head mounted for swinging movement in one direction and another to traverse a face being mined, an operating and control system for said head including: reversible fluid-pressure-operable motor means operable responsive to fluid under pressure to swing said head in one direction or the other across said face; a source of fluid under pressure; control valve and conduit means selectively effective to control the admission of fluid to said motor means to swing said head in one direction or the other; a first metering means connected to a source of fluid and operable responsive to fluid pressure to direct a measured volume of fluid to said motor means to swing said cutter head in one direction a fixed amount determined by said measured volume; a second metering means connected to a source of fluid and operable responsive to fluid pressure to direct another measured volume of fluid to said motor means to swing said cutter in another direction a fixed amount deter-

mined by the other measured volume of fluid; and control valve means connected to a source of fluid under pressure and selectively effective to direct fluid under pressure to one or the other of said metering means to actuate the latter to energize said motor means to swingably index said head a predetermined amount in one direction or the other.

2. In a continuous mining machine, a cutting head mounted for leftwise and rightwise swinging movement to traverse a face being mined, an operating and control system for said head including: reversible fluid pressure operable motor means operable to swing said head in either direction; a first metering means connected to a source of fluid and operable responsive to a fluid pressure to supply a measured volume of fluid to said motor means to swing said cutter head leftwise a fixed amount determined by said measured volume; a second metering means connected to a source of fluid and operable responsive to fluid pressure to supply another measured volume of fluid to said motor means to swing said cutter head rightwise a fixed amount determined by the other measured volume; control valve means connected to a source of fluid and effective selectively to direct pressure to either of said metering means; each of said metering means having means for varying the volume of fluid supplied thereby, and means interconnecting said varying means for concurrent operation to simultaneously change the volume of fluid supplied by both metering means.

3. In a continuous mining machine, a cutting head mounted for leftwise and rightwise movement to traverse a face being mined, an operating and control system for said head including: reversible fluid pressure operable motor means operable to swing said head in either direction; separate metering means operable to index said cutting head a predetermined proportion of its full swing in either direction; each of said metering means comprising a casing having a movable wall enclosing a metering chamber which is variable in volume upon movement of said wall; means biasing said wall toward a position of maximum volume for said chamber; stop means for limiting movement of said walls; conduit means connecting each of said chambers to a source of fluid and to said motor means; check valve means limiting flow, in each case, from the fluid source to the chamber and from the chamber to the motor means; and selectively operable means for moving one or the other of said movable walls to contract the chamber associated therewith to supply fluid under pressure to said motor means to index said head said predetermined proportion of its full swing in one direction or the other.

4. In a continuous mining machine, a cutting head mounted for leftwise and rightwise swinging movement to traverse a face being mined, an operating and control system for said head including: reversible fluid pressure operable motor means operable to swing said head in either direction; separate metering means operable to index said cutting head a predetermined proportion of its full swing in either direction; each of said metering means comprising a casing having a movable wall enclosing a metering chamber which is variable in volume upon movement of said wall; means biasing said wall toward a position of maximum volume for said chamber; stop means for limiting movement of said walls; conduit means connecting each of said chambers to

a source of fluid and to said motor means; check valve means limiting flow, in each case, from the fluid source to the chamber and from the chamber to the motor means; and other manually controllable means for swinging said head any desired variable amount in either direction.

5. In a continuous mining machine, a cutting head mounted for leftwise and rightwise swinging movement to traverse a face being mined, an operating and control system for said head including: reversible fluid pressure operable motor means operable to swing head in either direction; separate metering means operable to index said cutting head a predetermined proportion of its full swing in either direction; each of said metering means comprising a casing having a movable wall enclosing a metering chamber which is variable in volume upon movement of said wall; means biasing said wall toward a position of maximum volume for said chamber; stop means for limiting the range of movement of each of said walls; and adjusting means for concurrently varying the positions of both of said stop means to correspondingly vary the range of movement of both of said movable walls; conduit means connecting each of said chambers to a source of fluid and to said motor means; check valve means limiting flow, in each case, from the fluid source to the chamber and from the chamber to the motor means; and other means for swinging said head any desired variable amount in either direction.

6. In a continuous mining machine, a cutting head mounted for leftwise and rightwise swinging movement to traverse a face being mined, an operating and control system for said head including: reversible fluid pressure operable motor means operable to swing said head in either direction; separate metering means operable to index said cutting head a predetermined proportion of its full swing in either direction; each of said metering means comprising a casing having a movable wall enclosing a metering chamber which is variable in volume upon movement of said wall; means biasing said wall toward a position of maximum volume for said chamber; stop means for limiting movement of said walls; conduit means connecting each of said chambers to a source of fluid and to said motor means; check valve means limiting flow, in each case, from the fluid source to the chamber and from the chamber to the motor means; fluid pressure operable actuating means effective, when actuated, to move either of said walls to contract the chamber associated therewith for directing a measured volume of fluid therefrom to said motor means; and control valve means connected between said actuating means and a source of fluid under pressure and being selectively operable to connect either of said actuating means with said source of fluid under pressure to actuate either of said metering means to index said cutting head a predetermined proportion of its full swing in either direction.

7. In a continuous mining machine, a cutting head mounted for leftwise and rightwise swinging movement to traverse a face being mined, an operating and control system for said head including: reversible fluid pressure operable motor means operable to swing said head in either direction; separate metering means operable to index said cutting head a predetermined proportion of its full swing in either direction; each of said metering means comprising a casing having a movable wall enclosing a metering chamber which

is variable in volume upon movement of said wall; means biasing said wall toward a position of maximum volume for said chamber; stop means for limiting movement of said walls; conduit means connecting each of said chambers to a source of fluid and to said motor means; check valve means limiting flow, in each case, from the fluid source to the chamber and from the chamber to the motor means; fluid pressure operable actuating means for actuating each of said metering means; and control valve means connected between a fluid pressure source and said actuating means and between a fluid pressure source and said motor means and being selectively operable to direct pressure to one or the other of said actuating means to index said cutting head a predetermined proportion of its total swing in either direction, and being further selectively operable to apply pressure directly to said motor means to swing the cutting head a variable amount in either direction.

8. In a continuous mining machine, a cutting head mounted for swinging movement across a face being mined, an operating and control system for said head including: reversible fluid pressure operable motor means operable to swing said head in two directions; metering means operable to index said cutting head a predetermined proportion of its full swing in one direction or another; said metering means comprising a pair of cylinders each having a floating piston defining a variable volume metering chamber therewithin; each of said cylinders having means for biasing its piston toward a position of maximum volume for said chamber, and stop means for limiting the stroke of said piston; conduit and check valve means for each cylinder providing for flow from a source of fluid to the chamber and from the chamber to one side of the motor means in each case; a source of fluid under pressure; pressure conduits from said fluid pressure source to each side of said motor means and to the side of each floating piston exterior of the metering chamber; and control valve means associated with said pressure conduits operable selectively to direct fluid from said pressure source to either of said floating pistons for indexing the cutting head a predetermined amount in either direction, and further operable selectively to direct fluid from said pressure source to either side of said motor means to swing said cutting head a variable amount in either direction.

9. In a continuous mining machine, a laterally swingable cutting head, means for swinging said cutting head including reversible fluid pressure operated motor means connected with said head to reversely swing the same, a source of fluid under pressure including a tank and a pump connected thereto, a first metering means operable in response to fluid under pressure to direct a measured volume of fluid under pressure to said motor means, means for varying the volume of fluid displaced by said metering means to effect swinging of said cutting head in one direction a measured distance, a second metering means operable in response to fluid under pressure to direct a measured volume of fluid to said motor means, means for varying the volume of fluid displaced by said metering means to effect swinging of said cutting head in an opposite direction a measured distance, control valve means connected to said pump, fluid pressure conduits connected from said control valve means to said metering means

and operable to displace a measured volume of fluid therefrom, other fluid pressure conduits connected from said control valve means directly to said motor means, said control valve means being selectively operable to direct fluid under pressure to one or the other of said metering means, to displace a measured volume of fluid therefrom to said motor means and swingably index said cutting head a measured distance, and also to supply fluid under pressure directly to said motor means and swing said cutting head directly from pressure supplied by said pump under the control of said valve means.

10. In a continuous mining machine, a swingable cutting head, means for swinging said head by power including fluid pressure operated motor means, a source of fluid under pressure including a supply tank and a pump connected thereto, metering means supplying a measured volume of fluid to said motor means comprising a casing enclosing a metering chamber having a movable wall therein, a fluid conduit connecting said tank to one end of said casing, a check valve in said conduit, preventing reverse flow of fluid from said casing to said tank, a 25 second fluid conduit connecting said end of said casing to said motor means, a check valve in

said conduit preventing the back flow of fluid to said casing, control valve means, a fluid conduit connecting said pump to said control valve means, a fluid conduit connecting said control valve means to said casing, to supply fluid under pressure thereto, to move said movable wall in a direction to supply a measured volume of fluid under pressure to said motor means when said control valve means is in one position, and 10 means moving said movable wall to recharge said metering means from said tank through said first check valve means when said control valve means is in a neutral position, comprising spring means moving said movable wall in a 15 retractile direction along said casing, to effect the passage of fluid along said first conduit to said casing.
